Primary Examiner — Mark A Goodwin*Assistant Examiner* — Benjamin M Weeks(74) *Attorney, Agent, or Firm* — Chiesa Shahinian & Giantomasini PC(57) **CLAIM**

The ornamental design for an adaptor, as shown and described.

DESCRIPTION

FIG. 1 is a front perspective view of an adaptor according to our design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the drawing depict portions of the adaptor that form no part of the claimed design.

1 Claim, 5 Drawing Sheets(56)
